[57] ABSTRACT

A massaging apparatus comprises a hand-held caselike support housing an electric motor, a rotor driven by the motor, and a plurality of rollers rotatably mounted about axes equidistantly spaced apart from and parallel to the axis of the rotor. Said support includes a rim defining an open face of the support disposed in a plane generally parallel to the axis of the rotor, which rim can be applied against an area of a body to be massaged with said area lying in the path of said rollers during rotation of the rotor. An elastic sheet is removably mounted over said open face, and transmits impacts of the rollers to said area of a body being massaged.

5 Claims, 5 Drawing Figures

FIG.1

FIG. 2

FIG. 3

FIG. 4FIG. 5## MASSAGING APPARATUS

The invention relates to massaging apparatus.

Various types of massaging apparatus are known. Some are in the form of a brush, others include rollers or balls elastically or otherwise mounted in a frame, and others employ vibrating belts. With these known apparatus the massaging action generally takes place by a progressive lateral crushing. An important use of such massaging apparatus is the elimination of cellulitis. However, cellulitis involves deposits, or nodules, which cannot be eliminated by the blood or lymphatic flow but only by bursting the nodules accumulated in the connective tissues. To burst these nodules, the best results obtained to date have been by manual massage, by kneading, which treatment is not without pain to the person being massaged, or by massage with a jet of water or air at pressure or about 6 atmospheres.

An aim of the invention is to provide a massaging apparatus particularly suitable for the treatment of cellulitis, and which acts by percussion followed by a progressive lateral crushing.

According to the invention, a massaging apparatus comprises a support and a rotor mounted in the support, said rotor carrying at least one roller rotatably mounted about an axis parallel to and spaced apart from the axis of the rotor.

Preferably, the support includes a rim defining an open face of the support disposed at least approximately in a plane generally parallel to the axis of said rotor, which rim can be applied against an area of a body to be massaged with said area lying in the path of said at least one roller during rotation of the rotor. When the rotor is driven, the or each roller can thus be made to percute the treated area, and then provide a progressive lateral squashing analogous to a massage by kneading. The speed and direction of impact of the roller(s) can be varied by changing the orientation of the apparatus. Percussion is particularly efficient for the treatment of cellulitis, in view of the profound penetration upon impact, the incompressibility of the liquids contained in the tissues, and the relatively little possibility for the tissues to move apart.

An embodiment of a massaging apparatus according to the invention will now be particularly described, by way of example, with reference to the accompanying schematic drawings, in which:

FIG. 1 is a view in cross-section taken along line I—I of FIG. 4;

FIG. 2 is a cross-section of a removable attachment, taken along II—II of FIG. 3;

FIG. 3 is a plan view of the removable attachment;

FIG. 4 is a side elevational view of the apparatus; and

FIG. 5 is a plan view of the apparatus.

The apparatus shown comprises a main support 1 in the form of a hollow case or housing, for example in a moulded synthetic plastics material, in which a rotor 2 is rotatably mounted. Rotor 2 includes a main shaft 3 carrying at its ends four radial arms 4, 5, 6, 7 and 4', 5', 6', 7', respectively, with the adjacent arms disposed perpendicular to one another. The outer ends of parallel pairs of the arms spaced apart along shaft 3, namely 4, 4'; 5, 5'; 6, 6'; 7, 7', are interconnected by axles 8, 9, 10 and 11 respectively on which are freely rotatably mounted four members such as rollers 12, 13, 14 and 15. The rotor shaft 3 is mounted in bearings 19 and 20

formed in facing walls of the support 1 during moulding.

The arms with their axle, for example 4, 4' and 8, can be formed from a single rod whose ends are bent to 5 form the arms after fitting of the roller.

FIGS. 4 and 5 schematically show the means for driving rotor 2, namely an electric motor 16 and a reduction gear 17, which may include a gear change device 10 if desired. Motor 16 also carries a propeller blade 18 15 which is adapted to suck air in through an inlet (not shown) in the case for the purpose of cooling motor 16. An adjustable heating element may be placed between the motor 16 and the rotor 2 for a purpose which will be described later. Means can also be provided for setting the speed of the motor.

The support 1 includes an open portion or face, defined by a rim having two rim sections generally parallel to the axis of the rotor shaft 3, which can be covered by an interchangeable sheet 21 of a flexible elastic material, for example in rubber or in an elastic fabric, which is stretched between two bars 22 and 23 which are removably clipped into recesses 24 and 25 in opposed edges of said rim of support 1, and are held in place by the elasticity of the stretched sheet. The sheet 20 could be removably mounted onto said rim by other means; for example, the bars 22, 23 could be replaced by tubular members which slidably engage rails along 25 opposed edges of said rim.

As shown in FIGS. 2 and 3, the sheet 21 is a laminate 30 including two relatively thin layers 26, 27 of an elastically expandable and deformable material disposed about a relatively thick layer 28 of an elastically compressible material, for example a foamed rubber.

The part of support 1 about motor 16 is shaped to 35 form a hand grip, and the said rim of the open face of the support is adapted, in use, to be placed against an area of a body to be massaged with said area lying in the path of the working surfaces of the rollers 12, 13, 14 and 15 during rotation of rotor 2. The tissues and/or muscles of the treated area are thus exposed to the following actions. A percussion impact takes place where a roller moves in the direction towards the treated area (right hand part of FIG. 1 for a rotation of rotor 2 in the clockwise direction), from the point where the roller contacts the area, where movement of the roller is approximately perpendicular to the area, until the roller moves generally parallel to the area, as shown for roller 15 in FIG. 1. Percussion is thus exerted throughout an arc of movement of each roller, and the degree of percussion can be adjusted by exerting a greater or 45 lesser pressure on the handle of support 1.

Once a roller (e.g., 15) is in contact with the massaged area of the body, it continues its movement whilst carrying out a kneading which is effective especially when the roller has passed the position of roller 15 in FIG. 1; the kneading energy is also dependant on the pressure exerted on the handle of support 1. Three different degrees of intensity of action of the apparatus 50 are schematically indicated in FIG. 1 by three wavy lines 30, 31, 32 which represent momentaneous shapes of the skin and sheet 21 corresponding to three different pressures. By continuing its circular movement, the rotor 2 makes one roller (e.g., 15) move out of contact with the treated area while the following roller (e.g., 14) moves into contact. The rate of rotation of rotor 2 55 determines the frequency of the percussion which is preferably adjustable, by changespeed gears or by a

rheostat, between 25 and 100 impacts per second, preferably between 40 and 65. Apart from the percussion-producing impacts, the apparatus therefore has also a vibratory effect with a profound penetration generally perpendicular to the massaged area of the body.

By using an absorbing sheet such as the laminate shown in FIGS. 2 and 3, it is possible to modify the effect of the apparatus, or the type of treatment. Use with a thick absorbing sheet can produce a sedative effect, while use with a thin sheet, or none at all, is stimulating.

When a heater is incorporated between the rotor and the motor 16, the air delivered by blade 18, after having cooled the motor 16, may be further heated and delivered to the treated area of the body at a desired temperature in order to combine the massage with a heat treatment.

It would also be possible to vary the intensity of the massage by providing means for adjusting the position of the rim defining the open face of the support in relation to the rotor 2.

What is claimed is:

1. A massaging apparatus comprising:
a support having a rim which defines an open face of the support; the support defining a rotor axis;
a sheet mounted on said rim and extending across said open face, said sheet being a laminate including two relatively thin layers of an elastically expansible material and a relatively thick layer of an

elastically compressible material between said two relatively thin layers; and
rotor means mounted in the support for rotation about said rotor axis to move into contact with, and roll over, successive portions of said sheet and thereby to apply massaging effects.

5 2. An apparatus according to claim 1 in which said sheet and said rim have edges and include, at corresponding mutually opposed edges, means for releasably gripping an edge of the sheet to an edge of the rim and for holding the sheet elastically stretched between opposed ones of the edges of the rim.

10 3. An apparatus according to claim 1, including an electric motor mounted on said support for driving said rotor, and means for propelling air past said motor and said rotor.

15 4. An apparatus according to claim 3, additionally including heater means disposed in said support, between the electric motor and the rotor, for heating said air.

20 5. A massaging apparatus according to claim 1 wherein said rotor means defines at least one roller axis parallel to and radially spaced from said rotor axis, and includes roller means mounted on the rotor for rotation therewith and for rotation about the roller axis to roll over said successive portions of said sheet and thereby to apply said massaging effects.
